UNITED STATES PATENT OFFICE.

GEORGE F. BUTTERFIELD, OF STONEHAM, MASSACHUSETTS.

BOOT OR SHOE.

SPECIFICATION forming part of Letters Patent No. 399,130, dated March 5, 1889.

Application filed August 10, 1885. Serial No. 173,972. (No model.)

To all whom it may concern:

Be it known that I, GEORGE F. BUTTERFIELD, a citizen of the United States, residing at Stoneham, in the county of Middlesex and State of Massachusetts, have invented certain new and useful Improvements in Rubber-Soled Boots or Shoes; and I do hereby declare that the same are fully described in the following specification, and illustrated in the accompanying drawings.

The especial object of this invention is to provide an improved boot or shoe having a leather sole secured to it in any of the usual ways and a tread-surface of india-rubber subsequently applied over the entire bottom of the leather sole and permanently fixed thereon by a coating of cement and the process of vulcanization of the rubber. My invention includes a boot or shoe so made, and also the described process of manufacture, whereby a shoe otherwise completed is finished by the vulcanizing of a rubber outer sole upon its leather sole.

Heretofore complete rubber soles have been vulcanized independent of the shoe to which they were to be applied, and such soles were capable of attachment to shoe-bottoms by cementing, nailing, or sewing through the rubber and leather. It has also been proposed to provide combined rubber and leather soles, united by cement and vulcanizing previous to their attachment to the boot or shoe, leaving uncovered a suitable margin of the sole-leather, outside of the edges of the india-rubber, all around, for sewing, pegging, or nailing on the sole to the shoe through this uncovered margin.

In carrying out my invention I employ a suitable mold adapted to hold the boot or shoe in place and to receive in a proper-shaped cavity the necessary amount of the raw-rubber compound, applied after the coating of rubber cement directly upon the leather sole of the boot or shoe so held in the mold. This cavity will be tap-sole shaped, or sole-shaped, or sole-and-heel shaped, according as it is desired to apply the rubber in either of these forms to the bottom of the boot or shoe. In either case a recess is formed in the upper part of the mold to admit the body of the shoe, while the bottom of its leather sole fits closely over the cavity containing the rubber.

The drawings annexed illustrate a form of mold suitable for my purposes, showing the position of the shoe relatively to the rubber in the cavity of the mold. I, however, make no present claim on the mold, my invention in that respect being best shown in my application, Serial No. 186,313, filed December 21, 1885, for vulcanizing-mold. A brief reference to the parts shown in the drawings will serve to explain the process herein claimed.

Figure 1 is a longitudinal section through the cap of the mold in the plane of separation of the other two parts. Fig. 2 is a transverse section through the three parts at the line of the heel, and Fig. 3 a like view of the forward part of the mold. The lines *y* and *z*, Fig. 1, indicate the plane of the sections, Figs. 2 and 3.

The mold is hollow, its body in two parts, A and B, united by suitable fastenings, so as to close tightly around the shoe held in the recess between them. The mold is completed by a cap, C, bolted to the parts A and B and containing in a proper-shaped cavity the body of rubber, R. E is a lip formed on the parts A and B, to fit into the crevice where the upper leather and sole of the shoe meet to keep the rubber from the shoe-upper.

I prefer to first shape the portion of rubber compound to be used approximately to the recess by pressure in a suitable die, so that it will fit upon the sole and heel of the shoe when the mold is closed tightly. Steam-heat is then applied in a proper manner and the expansion and pressure shapes the rubber externally while being cured and causes it to adhere tenaciously to the leather sole, the bottom of which should be clean and fresh when the preliminary coating of rubber cement is applied, which increases the adhesion of the rubber to the leather by excluding air from them.

An advantage of my process, by which the leather sole is first secured to the boot or shoe and the rubber subsequently vulcanized to its sole, is that the leather sole is covered to its extreme edges, thus concealing the nails, pegs, or stitches and giving a water-proof bottom to the shoe, instead of leaving an uncovered margin all around it to receive the fastenings, which are exposed in the finished shoe.

I claim as my invention—

1. The described process of forming rubber-soled boots or shoes, consisting in first making the boot or shoe and securing its leather sole to it in any usual way, then applying to the bottom of such leather sole a coating of rubber cement and an outsole of raw-rubber compound, and subsequently curing the rubber sole and permanently affixing it to the leather-sole bottom by vulcanization, substantially as set forth.
2. A boot or shoe having a leather sole sewed, pegged, or nailed to the upper thereof,

and provided with a rubber outer sole secured by cement and vulcanization directly upon the bottom of the leather sole, so as to 15 conceal said sole and its fastenings, substantially as set forth.

In testimony whereof I hereto affix my signature in presence of two witnesses.

GEORGE F. BUTTERFIELD.
